UNITED STATES PATENT OFFICE.

WALTER S. ADAMS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

CAR-TRUCK.

1,120,639.

Specification of Letters Patent.

Patented Dec. 8, 1914.

Application filed March 30, 1914. Serial No. 828,138.

To all whom it may concern:

Be it known that I, WALTER S. ADAMS, a citizen of the United States, and a resident of the city and county of Philadelphia, 5 State of Pennsylvania, have invented a new and useful Improvement in Car-Trucks, of which the following is a specification.

The object of my invention is to provide a suitable pivoted car truck for surface cars 10 or other cars, as may be desired, in which the frame is provided with two upwardly arched semi-elliptic springs, and each spring is surmounted by a coiled spring on top of which is a cap from which are suspended 15 suitable links that extend below the arch of the semi-elliptic spring, and the links on opposite sides of the truck are united by means of a suitable bolster, from which the car body may be supported in the conventional way.

For a more particular description of my invention, reference is to be had to the accompanying drawings, forming a part hereof, in which—

25 Figure 1 is a side elevation of a truck provided with my improvement. Fig. 2 is a sectional view, taken on the line 2—2 of Fig. 1, looking in the direction of the arrows. Fig. 3 is a sectional view, taken on the line 30 3—3 of Fig. 2, looking in the direction of the arrows.

Throughout the various views of the drawings, similar reference characters designate similar parts.

35 My improved truck 1 has the usual side frames 2, pedestals 3, wheels 4 and axles 5, all of which may be of the usual construction. It also has the usual transom 6 and tie-bars 7 which may be of any suitable 40 form. The pedestals 3 are each provided with suitable seats 8 which support the ends of the upwardly arched semi-elliptic springs 9 so that these ends may move longitudinally of the truck, but not transversely. Each 45 spring 9 has a suitable band 10 at or about its center, and on top of this is a suitable seat 11, which carries a coiled spring 12, and this spring is surmounted by a suitable cap 13 which has side seats formed by the 50 lugs 14 and these seats carry suitable hangers 15 which extend below the level of the band 10 and are united at their lower ends

by means of a suitable connection 16, preferably made substantially as shown, and this connection 16 carries a bolster 17, one connection for each end of the bolster. The bolster 17 may be made in any suitable way, as with an upper bar 18 and a lower bar 19, which are arranged and disposed so as to carry suitable side bearings 20, and a center 55 bearing not shown, in the conventional manner. The side bearings 20 carry suitable rub-plates 21 which are preferably fixed thereto and adapted to engage corresponding plates 22 fixed to the transoms 6 of the 60 frame 2 by means of suitable bolts, or otherwise.

From the foregoing description it will be observed that the weight of the car body is borne by the bolster through the side and 70 center bearings and from thence is carried to the connection 16 and from them through the hangers 15 to the cap 13 and then down on the coiled spring 12 to the straps 10 through the lower spring seat 11 and from 75 thence along each end of each spring 9 to the frame 2 of the truck. By this construction all shocks and jolts incidental to the use of the truck will be transmitted to the car body, if at all, through two sets of 80 springs, a set of leaf springs and a set of coiled springs, so that the bolster of each truck is carried with a freedom from all violent jars and jolts.

While I have shown and described one embodiment of my invention, it is obvious that it is not restricted thereto, but is broad enough to cover all structures which come within the scope of the annexed claim.

Having thus described my invention, what I claim is:

In a truck of the class described, side frames, an upwardly arched spring carried by each side frame, a coiled spring carried by each leaf spring and mounted on top of 95 the same, caps on said coiled springs, hangers carried by said caps extending on each side of said leaf springs, connections between said hangers, and a bolster carried by said connections.

WALTER S. ADAMS
